Primary Examiner — Ian Simmons*Assistant Examiner* — Khawaja Anwar(74) *Attorney, Agent, or Firm* — NSIP Law(57) **CLAIM**

We claim the ornamental design for an ice machine for refrigerator, as shown and described.

DESCRIPTION

FIG. 1 is a front perspective view of an ice machine for refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is a bottom perspective view thereof.

(Continued)

The broken lines in the figures depict environmental subject matter and form no part of the claimed design.

1 Claim, 6 Drawing Sheets
